UNITED STATES PATENT OFFICE.

JACOB J. RAITHEL AND CHRISTIAN H. RAITHEL, OF ST. LOUIS, MISSOURI.

CLOTHES-LINE CLAMP.

No. 921,458.

Specification of Letters Patent. Patented May 11, 1909.

Application filed August 5, 1907. Serial No. 387,196.

To all whom it may concern:

Be it known that we, JACOB J. RAITHEL and CHRISTIAN H. RAITHEL, citizens of the United States of America, residing at the 5 city of St. Louis, in the State of Missouri, have invented certain new and useful Improvements in Clothes-Line Clamps, of which the following is a full, clear, and exact description, reference being had to the accompanying drawings, forming part of this specification.

Our invention relates to clamps for the reception of a clothes line and has for its object to produce a clamp of this character that is 15 of simple and efficient construction and into which a clothes line may be easily and quickly inserted to be held by the clamp in any desired degree of tautness.

Figure I is a perspective view of our clamp 20 shown attached to a support and with a fragment of a clothes line clamped therein. Fig. II is a side elevation of the clamp. Fig. III is a cross section taken on line III-III of Fig. II.

25 In the accompanying drawing, A designates a fragment of a post to which our clamp is shown applied and B is a fragment of a clothes line.

30 1 designates a bracket which comprises a flat face body having a side flange 2 located at the rear edge of the body. The side flange 2 is of curved shape and it has an inner gripping face 3.

35 4 is a fastening screw that is rigidly mounted in the bracket 1 and projects rearwardly therefrom. This screw is adapted to be mounted in a post similarly to the manner in which it is shown inserted into the post A. The bracket 1 is of approximately 40 quadrant shape and at its upper edge is a curved open slot 5 that extends inwardly from the upper edge of the body and is adapted to receive a member to be herein-after more particularly mentioned.

50 6 designates an eccentric block also of approximately quadrant shape that is pivotally connected at its front end by a bolt 10 to the front end of the flat body of the bracket 1 within the recess formed by the curved flange at a point near the junction of the angular edges of the front of said body. The point of pivotal connection between the eccentric block and the bracket is so located that the greatest portion of said block is below 55 said point in order that the lower part of the inner edge of the eccentric block may be

caused to be presented in proximity to the inner side of the lower end of flange 2 of the bracket to move to and from said flange to a sufficient degree to permit of a clothes line 60 being inserted between said lower part of the inner edge and said flange. The lower part of the inner edge of the eccentric block is serrated as seen at 7 and in the upper part of the inner edge and the upper edge of the 65 block is a corner groove 8 of approximately V-shape to provide a bite for the clothes line. 9 is a limitation stud that projects from the side of the eccentric block which faces the flat body of the bracket 1 and 70 which is adapted to enter and travel in the curved slot 5 in said body. This stud serves to restrict the degree of downward and rearward movement of the eccentric block in order that said block may only descend to a 75 restricted degree and will therefore always be retained in a position to readily grip a clothes line. By keeping the eccentric block in close proximity to said flange its gripping face is always in such position that 80 it is only necessary to introduce the clothes line between it and the gripping face of the bracket flange and exert a downward pull upon said line and when the line is released the eccentric block is automatically carried 85 upwardly and forwardly toward the bracket flange when the portion of the line drawn through the clamp is released and the stress in the line is permitted to become imposed upon the eccentric block. When the line is 90 in position in the clamp it occupies the corner groove at the top of the inner edge of the eccentric block and the walls of this groove serve to prevent lateral displacement of the line while it is in engagement with the 95 eccentric block.

100 It is to be observed that in our clamp the eccentric block partakes of an upward movement toward the gripping flange of the bracket when the clothes line fitted in the clamp exerts a pull upon the eccentric block and acts to tightly bind the line in the clamp. In this connection we desire to call attention to the fact that it is only necessary to exert a downward pull upon the extremity of the line in drawing the line taut and the line will become automatically clamped when its extremity is released. It will be seen that the construction of the clamp by which the operation stated is rendered possible makes it a much easier matter to adjust 105 the line in the clamp and tighten it by a 110

downward pull instead of an upward pull as is necessary in clothes line clamps of other constructions.

We claim:

- 5 A clothes line clamp comprising a bracket of approximately quadrant shape having a flat face, a segmental flange at the rear edge of the body, and an inwardly curved open slot in the upper edge of the body, and a
10 block of approximately quadrant shape pivoted eccentrically at its forward portion to the forward portion of the body of the

bracket, and having an approximately V-shaped groove in its rear upper corner providing a bite for the line, a serrated gripping part at its rear lower corner, and a transversely arranged limitation stud working in the inwardly curved open slot of the body.

JACOB J. RAITHEL.
CHRISTIAN H. RAITHEL.
